UNITED STATES PATENT OFFICE.

EMERY C. HODGES, OF FARMER CITY, ILLINOIS.

DESIGN FOR A CORNER-STONE FOR BURYING-LOTS.

SPECIFICATION forming part of Design No. 32,073, dated January 2, 1900.

Application filed November 14, 1899. Serial No. 736,994. Term of patent 14 years.

To all whom it may concern:

Be it known that I, EMERY C. HODGES, a citizen of the United States, residing at Farmer City, in the county of De Witt and State of Illinois, have invented a certain new and original Design for Corner-Stones for Burying-Lots, of which the following is a specification.

My invention relates to a new and original design for corner-stones for burying-lots; and the object of my invention is the provision of a beautiful and ornamental device for marking the corners of burying-lots to show the extent of the corner's angle.

To attain the objects, my invention consists of a marker for this purpose having new and original decorations, as fully set forth in the accompanying drawings, in which—

Figure 1 is a perspective view of the marker, taken from the interior of the lot; and Fig. 2 is a similar view taken from the exterior of the lot.

Referring to the drawings, A designates one arm or, rather, trunk of the marker, and B designates the branch or limb, which is at an angle to the trunk, the trunk and limb being covered with corrugations or representations of bark C of a tree. They are further pro-

vided with knobs or knots D, which represent where branches have worn or been cut off from the trunk and limb. At the angle 30 upon the interior where the trunk and limb meet are the decorative leaves E, which extend from the same meeting-point upon the inside of the trunk and limb, respectively, upon the top of both, where their ends are 35 some distance apart. Also climbing upon the top side of each are the vines or branches F, having the small leaves G branching out therefrom.

From this description, taken in connection 40 with the drawings, it will be seen that I provide a very ornamental, original, and useful design for corner-stones for burying-lots.

What I claim as new, and desire to secure by Letters Patent, is— 45

The design for a corner-stone for a burying-lot, as herein shown and described.

In testimony whereof I affix my signature in presence of two witnesses.

EMERY C. HODGES.
